CLAIM

The ornamental design for a food tray, as shown and described.

DESCRIPTION

FIG. 1 is a perspective view of the food tray, showing the present design.

FIG. 2 is a front view thereof.

FIG. 3 is a rear view thereof.

FIG. 4 is a right side view thereof.

FIG. 5 is a left side view thereof.

FIG. 6 is a top view thereof.

FIG. 7 is a bottom view thereof.

FIG. 8 is a perspective view of a bottom plate of the food tray.

FIG. 9 is a front view of the bottom plate of the food tray.

FIG. 10 is a rear view of the bottom plate of the food tray.

FIG. 11 is a right side view of the bottom plate of the food tray.

FIG. 12 is a left side view of the bottom plate of the food tray.

FIG. 13 is a top view of the bottom plate of the food tray.

FIG. 14 is a bottom view of the bottom plate of the food tray.

FIG. 15 is a perspective view of a middle plate of the food tray.

FIG. 16 is a front view of the middle plate of the food tray.

FIG. 17 is a rear view of the middle plate of the food tray.

FIG. 18 is a right side view of the middle plate of the food tray.

FIG. 19 is a left side view of the middle plate of the food tray.

FIG. 20 is a top view of the middle plate of the food tray.

FIG. 21 is a bottom view of the middle plate of the food tray.

FIG. 22 is a perspective view of a top plate of the food tray.

FIG. 23 is a front view of the top plate of the food tray.

FIG. 24 is a rear view of the top plate of the food tray.

FIG. 25 is a right side view of the top plate of the food tray.

FIG. 26 is a left side view of the top plate of the food tray.

FIG. 27 is a top view of the top plate of the food tray; and,

FIG. 28 is a bottom view of the top plate of the food tray.
